(57) **CLAIM**

The ornamental design of crotch for overalls, as shown and described.

DESCRIPTION

FIG. 1 is a front elevational view of a first embodiment of the crotch for overalls showing my new design;

FIG. 2 is a front elevational view of the crotch for overall of FIG. 1 in an alternate position;

FIG. 3 is a front elevational view of a second embodiment;

FIG. 4 is a front elevational view of the crotch for overall of FIG. 3 in an alternate position;

FIG. 5 is a front elevational view of a third embodiment

FIG. 6 is a front elevational view of the crotch for overall of FIG. 5 shown in an alternate position; the top edge of the inner layer has an opening for the fly which is to be covered by the flap.

FIG. 7 is a front elevational view of a fourth embodiment;

FIG. 8 is a front elevational view of the crotch for overall of FIG. 7 shown in an alternate position;

FIG. 9 is a front elevational view of a fifth embodiment; and, FIG. 10 is a front elevational view of the crotch for overall of FIG. 9 shown in an alternate position.

The broken lines are for illustrative purposes only and form no part of the claimed design.

The broken lines at the bottom of the waistband define the bounds of the claimed design and form no part thereof.
